(57) **CLAIM**

The ornamental design for a storage device case, as shown and described.

DESCRIPTION

FIG. 1 is a perspective view of a storage device case showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a enlarged view of a broken line circle portion 8 as shown in FIG. 2.

The dash-dash broken lines shown in the drawings depict portions of the storage device case that form no part of the claimed design. The dot-dash broken line circles are included for the purpose of delineating the bounds of the enlarged view and form no part of the claimed design.
